CLAIM

I claim the ornamental design for a wildlife feeder, as shown and described.

DESCRIPTION

FIG. 1 is a front perspective view of a wildlife feeder showing my new design;

FIG. 2 is a front elevation view of the wildlife feeder illustratively shown resting on a support surface;

FIG. 3 is a top view thereof;

FIG. 4 is a left side elevation view thereof;

FIG. 5 is a rear elevation view thereof;

FIG. 6 is a right side elevation view thereof; and,

FIG. 7 is a bottom view of the wildlife feeder.

Any portions shown in broken line are not claimed.
